UNITED STATES PATENT OFFICE.

GEORGE WALTERS, OF DIXFIELD, MAINE.

SEWING KIT.

1,081,070.

Specification of Letters Patent.

Patented Dec. 9, 1913.

Application filed February 28, 1912. Serial No. 879,422.

To all whom it may concern:

Be it known that I, GEORGE WALTERS, a citizen of the United States, and resident of Dixfield, in the State of Maine, have invented certain new and useful Improvements in Sewing Kits, of which the following is a specification accompanied by drawings.

The invention relates to sewing kits for mending gloves, hosiery and other articles, and its object is to combine in very compact form a number of useful articles, preferably including fine thread, darning thread, thimble, needles, a darning head and a finger form.

15 In the preferred form of my invention, it combines means for holding a thimble and means in coöperation with the thimble for holding a number of spools and needles, respectively, in two receptacles within the head and handle of the device.

20 In the accompanying drawings, Figure 1 shows the preferred form of the invention, partly in central cross section, Fig. 2 is the upper portion or darning head thereof, Fig. 25 3 is a view of the lower member, and Fig. 4 is a detailed sectional view of a modification.

25 In the preferred form, the outer or container elements comprise two members, each having a receptacle, and a thimble forms a closure for one of the receptacles and the member containing such receptacle forms a cover or closure for the other receptacle.

30 One member *b* is made of rounded, bulbous form, suitable for a darning head or ball, and internally has a large cylindrical recess *c* fitted to appropriate spools with a smaller extension *d* of such recess for receiving the end of a smaller spool. The 35 other outer member comprises a handle *f*, of form suitable for fitting within the finger of a glove, or the like, to be mended, and a spring flange *g* attached to fit and be snugly and resiliently retained within the 40 recess *c* of the head, a recess *h* within such flange for fitting and holding a thimble, and a long axial recess which constitutes a receptacle *j* for needles. The peripheral flange *k* abuts externally against the end of the 45 head *b*. Saw cuts or slots *g'* divide the flange *g* into a plurality of spring members. These saw cuts or slots preferably extend all the way down to the flange *k*, whereas the bottom against which the thimble *l* rests is somewhat above the flange *k* in order that the spring flange which tightly fits the thim-

ble shall have sufficient resilience to insure its holding the thimble in place. Preferably, therefore, the spring flange serves both to hold the handle to the head and to hold the thimble in the handle. If the outer parts are made of wood or similar yielding material, the flange may be made sufficiently resilient without slotting it, but this requires an inconvenient accuracy of construction and fit. The upper end of the flange *g* is beveled internally and externally to facilitate inserting the thimble and inserting the flange into the head.

The thimble *l*, when fitted into place, forms a cover for the needle receptacle *j* and prevents the needles *m* being displaced.

Within the head are one or more spools *p* of relatively large diameter, for example, two, which are relatively proportioned to externally fit approximately the recess *c* in diameter, and longitudinally to be held and approximately fit between the end of the recess and the flange *g*. Internally the spools *p* have a large axial recess and one or more, preferably three or more, spools *r* of smaller diameter, the smaller spools being received at one end in the extension *d* of the recess *c*, and at the other end fitting around the raised or slightly pointed end of the thimble *l* which projects and is received within the bore of the larger spool, as shown in Fig. 1. The larger spools may conveniently carry darning silk or cotton and the smaller spool fine thread suitable for mending clothes and fine hosiery.

In the modification shown in Fig. 4, the thimble *l* is reversed and extends down into a recess in the handle *f'*, its edge being held, however, as before, by the spring flange *g*. It will be seen that in this position one or two more of the smaller spools *r* may be carried, being partly received within the thimble. In this modification, the length of the handle available for the needle recess is lessened by nearly twice the length of the thimble, and, if it is desired to include a bodkin or very long needles, these may be placed within the bore of the smaller spools and extend down into the thimble.

It will be seen from Fig. 1 that I have so combined the shapes and locations of the various articles and members as to combine a great many useful articles in approximately the minimum possible space, and so adapted the parts to each other that they are all substantially retained in an orderly

and convenient manner, ready for instant use. It will be seen that for some purposes some features of the invention may be used without others.

5 I claim the following:

1. In combination in a sewing kit, a head having a chamber adapted to hold spools, and a handle having a chamber adapted to hold needles and opening into the spool 10 chamber when the handle is in place, said handle having a resilient flange which fits the said head and is internally adapted to engage and resiliently hold a thimble in position to separate the contents of the two 15 chambers.
2. A sewing kit comprising a bulbous head forming one receptacle, and a handle

forming a second receptacle, the mouths of the said receptacles being opposed and open into each other, and a separating means dividing the receptacles comprising a thimble, the said handle having a spring flange comprising a plurality of spring members which frictionally clasp and hold said separating means, said handle also engaging and fitting 25 the receptacle in the bulbous head.

In testimony whereof I have signed this specification in the presence of two subscribing witnesses: this 21st day of February, 1912.

GEORGE WALTERS.
